CLAIM

The ornamental design for a combined checkbook holder with timepiece, as shown and described.

DESCRIPTION

FIG. 1 is a front elevational view of a combined checkbook holder with timepiece, showing our new design, the rear view being a mirror image thereof without the timepiece;

FIG. 2 is a side elevational view thereof;

FIG. 3 is a top plan view thereof; and

FIG. 4 is a bottom plan view thereof.

FIG. 2

FIG. 3

FIG. 1

FIG. 4
